APPARATUS FOR CLEANING TANKS AND
THE LIKE

Raymond C. Grein, Rochester, N. Y.

Application August 12, 1948, Serial No. 43,823

5 Claims. (Cl. 210—207)

1

The present invention relates to a method of and apparatus for cleaning the interiors of tanks and similar liquid containers and it has for its general object to provide an improved method and a simple and portable apparatus whereby such a tank containing a body of liquid at a high or low level may have its walls thoroughly cleaned of sludge and sedimentary matter and the liquid body restored thereto in a filtered condition, all in one operation. In other words the tank does not have to be first emptied of its contents as in other techniques, flushed with other solutions or liquids, or free access gained to its interior.

These and other desirable objects are accomplished by the construction disclosed as an illustrative embodiment of the invention in the following description and in the accompanying drawings forming a part hereof, in which:

Fig. 1 is a front elevation of both a conventional liquid holding tank and, beside it, in co-operative relationship therewith an apparatus constructed in accordance with and illustrating one embodiment of the invention through the use of which apparatus the improved method may be practiced, a portion of the tank wall being broken away.

Fig. 2 is a top plan view of the apparatus with the draining and discharge hoses broken away;

Fig. 3 is a side view of the apparatus with the discharge hose in section and the draining hose broken away;

Fig. 4 is an enlarged vertical central section through the filter with parts broken away; and

Fig. 5 is an enlarged central vertical section through the preliminary screen strainer.

The same reference numerals throughout the several views indicate the same parts.

Referring more particularly to the drawings, A indicates a conventional oil storage tank such as is commonly used in residences for domestic heating installations and though the invention is not to be considered so limited the following description will be addressed specifically, for convenience, to its application to the cleaning of such tanks to prevent foreign matter from being carried to the oil burner through the oil feeding connection. In the illustration, the tank is practically full, the oil level being indicated at B. Were it suddenly discovered, under such circumstances, that the oil and tank were foul and were passing foreign matter admixed with the oil to the fuel line, causing stoppages at the burner, it would, in past practices, be necessary to drain off the contents, clean the oil, clean the

2

tank, and refill it. Sludges form on the bottom and submerged walls due principally to sedimentary deposits, scale, and rust, the latter caused largely by water of condensation settling at the bottom. With the present invention, draining the tank in order to clean it is not necessary.

There is provided a portable apparatus that may be easily carried and transported to and from the home or other scene of operations and embodying an open table base 10. Hung from and beneath the table portion 12 thereof is a motor 14 controlled by a switch 16 and driving, through a belt 18 a suitable pump 20 which, in the present instance is a centrifugal pump. The intake 22 of the latter is fitted with a preliminary oil cleaning screen casing or strainer 24 (Fig. 5). The strainer embodies a removable screen cylinder 24 carried by a plug 26 and seated in the interior wall 28. A nipple 30 on the casing forms attachment for a flexible drainage hose or pipe 32 terminating at its free end in a nipple or wide capacity mouth 34.

The discharge port of the pump delivers to a pump chamber 36 from which a pipe section 38 leads through a union 39 to a sight gage 40 of transparent character through which the flow of liquid may be observed at any time during the operation so that its condition as to the presence of foreign matter may be noted. The gage or sight glass 40 is preferably provided with a rotary vane 41 turned by the flow of liquid, so that the readily observable speed of rotation of the vane gives the operator a clear indication of the rate of flow. The gage is supported above the table 12. Thence the flow passes through a pipe section 42 to the intake 44 of a filter casing 46 detachably supported by suitable brackets 47 from the table 12. This filter unit is of an available type and need not be described in detail. Suffice it to say that a correspondingly crimped wool felt and screen cloth filtering medium 48 is slipped onto a permanent finned insert form 50, the ends of which are closed by the heads 52. The inflowing oil (arrows 54) passes therethrough to a foraminous inner tube 56 on a finned central support 58 and is forced down the same (arrows 60) to issue at a discharge outlet connection 62. To this connection is attached 50 through a nipple 64, a flexible discharge hose 66 terminating in a high velocity jet nozzle 68.

In operation under the condition first described, the apparatus is transported to the scene and placed approximately as shown. Drain or suction hose 32 is inserted in a top hung D with which

the tank is provided near one end thereof until the mouth 34 of the pipe is adjacent the bottom of the tank. Discharge hose 66 is similarly inserted in another like bung hole E near the opposite end of the tank so that its high velocity nozzle 68 rests on the tank bottom. The starting switch 16 is operated (after the electric supply cord, not shown, has been plugged into a convenient outlet) to start operation of the pump 20, the flow travelling as described from intake 34 through the gage 40 and filters 24 and 46 to the nozzle. This latter is moved around by manipulating the flexible hose from the exterior so that it lashes about inside and directs the issuing flow of circulating oil in diverse multiple directions and impinges the stream against the submerged walls at various angles to cause extreme turbulence in the oil body. This scouring action dislodges dirt particles and holds them in suspension until caught at the strainer 24 or the filter 46. In the meantime the condition of the oil is being watched through the sight gage 40.

When it is observed that the oil is running clear, the operation is discontinued, the tank is clean, the oil is clean, and it is still in the tank. Water of condensation that has settled at the bottom of the latter will be trapped in the bottom of the filter case 46 and may be drawn off through a valve controlled drain pipe 19.

For ease of portability of the apparatus, the union 39 may be disconnected, whereupon the sight glass 40, piping 42, and filter unit 46 may be lifted together off of the table 12, since the filter unit 46 merely rests loosely on the brackets 47 which engage the under surface of the horizontal ring on the filter casing, as seen in Fig. 1. The table 12 and the motor and pump mounted thereon are sufficiently light to be carried readily as one piece, while the filter unit 46 and pipe 42 and sight glass 40 are sufficiently light to be carried readily as another piece. Then it is but the work of a moment to connect or disconnect the union 39 and to drop the filter casing into or lift it up from the bracket arms 47.

It is seen from the foregoing disclosure that the above mentioned objects of the invention are admirably fulfilled. It is to be understood that the foregoing disclosure is given by way of illustrative example only, rather than by way of limitation, and that without departing from the invention, the details may be varied within the scope of the appended claims.

What is claimed is:

1. Portable apparatus for filtering a liquid, said apparatus comprising a supporting table having downwardly extending leg portions to maintain the table in an elevated position, a liquid pump and a motor for driving said pump suspended from and depending below said table, a filter unit mounted above said table, said filter unit having an upstanding elongated casing and a flange extending outwardly therefrom at an elevation materially above the bottom thereof, a plurality of bracket arms mounted on said table and extending upwardly therefrom in laterally spaced relation to each other, said bracket arms being arranged to receive said casing between them with said flange resting on said bracket arms, conduit means interconnecting said pump and filter unit, and a readily detachable connec-

10
15

tion in said conduit means between said pump and said filter unit so that when said connection is disconnected said filter unit may be simply lifted off of and out from between said bracket arms and may be transported separately from said table and pump and motor, to render said apparatus more readily portable.

2. A construction as described in claim 1, further including a flexible inlet conduit operatively connected to the inlet of said pump, a flexible outlet conduit operatively connected to the outlet of said pump, and a restricted orifice nozzle at the discharge end of said outlet conduit to produce a relatively high velocity jet of liquid issuing from said outlet conduit.

3. A construction as described in claim 1, further including a strainer unit operatively connected to the inlet of said pump to strain liquid before it reaches said pump, said filter unit being operatively connected to the outlet of said pump.

4. A construction as described in claim 3, in which said strainer unit comprises a casing having inlet and outlet orifices in approximate alignment with each other and a lateral extension provided with a screen orifice, and an approximately cylindrical straining screen inserted in said casing through said screen orifice and with its cylindrical axis at a substantial angle to a line joining said inlet and outlet orifices.

5. Apparatus as defined in claim 1, further including suction conduit means operatively connected to the inlet of said pump and having a suction end adapted to be inserted downwardly in a top opening in a liquid tank to extend down therein to a point near the bottom of the tank, and discharge conduit means operatively connected to said filter unit to receive the liquid discharged from said filter unit, said discharge conduit means having at its discharge end a restricted high velocity nozzle adapted to be inserted downwardly in a top opening of a liquid tank to extend down therein to a point near the bottom of the tank to produce, when said pump is in operation, a high velocity liquid jet to impinge on the bottom of the tank and stir up sediment therein.
